UNITED STATES PATENT OFFICE.

CHARLES F. LORD, OF MECHANIC FALLS, MAINE, ASSIGNOR OF ONE-HALF
TO ELLIS S. GRAY AND FRANK E. HERSEY, OF SAME PLACE.

GANG-PUNCH.

SPECIFICATION forming part of Letters Patent No. 613,840, dated November 8, 1898.

Application filed February 15, 1898. Serial No. 670,350. (No model.)

To all whom it may concern:

Be it known that I, CHARLES F. LORD, of Mechanic Falls, in the county of Androscoggin and State of Maine, have invented certain new and useful Improvements in Gang-Punches, of which the following, taken in connection with the accompanying drawings, is a specification.

My invention relates to "gang-punches," and to that particular class of such punches as are adapted to punching a series of holes in the quarters of lace-boots for the reception of eyelets or lacing-studs; and it consists in certain novel features of construction, arrangement, and combination of parts, which will be readily understood by reference to the description of the accompanying drawings and to the claims hereto appended and in which my invention is clearly pointed out.

Figure 1 of the drawings is a plan of a machine embodying my invention. Fig. 2 is a front end elevation. Fig. 3 is a side elevation. Fig. 4 is a sectional elevation, the cutting plane being on line $x-x$ on Fig. 1. Fig. 5 is a vertical transverse section through one pair of the punching arms and tools on line $y-y$ on Fig. 4. Fig. 6 is a plan of the adjusting-plate for regulating the distance apart of the several punches.

In the drawings, A is the bed or base plate of the machine, having formed in one piece therewith or secured thereto the uprights A' , A^2 , and A^3 .

B is a table secured upon the upright A' and having cut through it the slot B' for the passage of the punches, as shown in Figs. 1 and 4.

C is the driving-pulley, having firmly secured thereto the pinion D and mounted loosely upon a stud set in the ear A^4 , projecting upward from the base-plate A, said pinion engaging with the teeth of the spur-gear E, loose on the shaft F, mounted in bearings in the uprights A^3 A^3 and having firmly secured thereon just inside of each of said bearings an eccentric G, upon which is mounted the lower end of an eccentric-rod H, the upper ends of which eccentric-rods are connected together by the rod H' , as shown in Figs. 1, 2, and 4.

The upright A^2 has secured to its upper edge the rearwardly-projecting flange-plate a , having its upper surface serrated, and has formed therein a series of slots b , above each of which is mounted a plate c , having its under surface serrated to engage the serrated surface of the plate a and provided with a perforation for the passage of the pivot-bolt d , which is screwed into the rear end of the arm I, which rests upon the plate c , said pivot-pin or bolt d being provided with the clamping-nut d' and the check-nut d'' , as shown in Figs. 3 and 4.

The arms I are provided at their rear ends with the upwardly-projecting branches I' and rest upon and are pivoted to the plates c at their rear ends and rest near their front ends upon the upright A' and have set in their front ends the tubular cutting-punches e , as shown in Figs. 4 and 5.

J are arms pivoted to the branches I' of the arms I, having adjustably set in their front ends the downwardly-projecting anvil-blocks f , against which said punches e cut, and said arms J are each provided with a slot g , extending longitudinally thereof, through which the rod H' passes, so that when the shaft F is revolved the arms J will be moved about their pivotal connections to the branches I' to raise and depress the front ends of said arms J and their anvil-blocks f .

Beneath the table B and between it and the front ends of the arms I is fitted in suitable guideways the plate L, provided with a series of diverging slots h h , through which the punches e project, and also with the slot h' , through which the bolt i , fixed in the table B, projects, and is provided with the clamping-nut j to firmly clamp said plate in its adjusted position, said plate being moved outward or inward to vary the distances between the punches e by means of the lever M, pivoted at k to the under side of the table B and engaging a pin l , set in the under side of said plate, as shown in Figs. 1 and 3.

The shaft F has firmly secured thereon, just outside the right-hand upright A^3 , one member N of a clutch, provided with the shoulder m , the cam-surface m' , and the radial socket m^2 , and the gear E has formed thereon or se-

cured thereto the other member N' of said clutch, provided with the shoulder n, arranged to engage the shoulder m to revolve said shaft F, and with the circumferential groove n', 5 with which the shipper-fork O, secured to the shipper-rod O', engages, as shown in full lines in Fig. 2 and in dotted lines in Fig. 3.

The rod O' is mounted and movable end- 10 wise in suitable bearings in the uprights A³ A³ and is surrounded, between the right-hand upright A³ and the collar o, by the coiled spring P, the tension of which tends to move said rod O', the shipper O, and the gear E toward the left of Fig. 2.

15 The shipper-fork O is formed from a plate of metal and has three right-angle bends, thereby giving to it two vertical sections and two horizontal sections parallel to each other, and is secured to the rod O' by the vertical 20 section connecting the two horizontal sections, as shown in Fig. 2.

R is a locking-bolt fitted to bearings in the horizontal sections of the shipper-fork O in a vertical position and having secured thereon 25 the collar p, between which and the lower horizontal section of said shipper-fork said bolt is surrounded by the spring q, the tension of which presses said bolt upward into contact with the clutch member N, as shown 30 in Fig. 2.

The bolt R is acted upon by the cam-surface m', formed upon the clutch member N, to move said shipper-fork O and its rod O' toward the right of Fig. 2 against the tension 35 of the spring P, thereby disengaging the clutch member N' from the member N, so that the gear E and clutch member N may revolve freely upon the shaft F, while the motion of said shaft is arrested by the shoulder s on the 40 clutch member N coming in contact with said bolt R and is locked in said arrested position by the bolt R being pressed into the socket m² in said clutch member N.

The bolt R is connected by a wire or other 45 suitable means to a treadle upon the floor, but not shown, by depressing which to a sufficient extent to move the upper end of the bolt R below the periphery of the cam portion of the clutch member N the tension of 50 the spring P will cause the clutch members to be engaged and the shaft F to be revolved.

The right-hand arm I has secured thereto a block r, provided with a forwardly-projecting pin r', upon which is adjustably secured 55 the gage r², and said block r also has set therein the bent rod r³, upon the end of which is adjustably secured the gage r⁴, and the left-hand arm I has secured thereto the block t, provided with the pin t', upon which is ad- 60 justably secured the gage t², and said block also has secured therein the bent rod t³, upon which is adjustably secured the gage t⁴, as shown in Figs. 1, 2, 3, and 4.

It will be observed that the tool-carrying 65 arms I and J may be readily adjusted end- wise, so as to adapt the positions of the several punches and their anvil-blocks to any

particular curve of the shoe or boot quarter, and by a proper adjustment of the plate L the front end of the said arms I and J may 70 be moved toward or from each other to vary the distance between the several punches.

The machine illustrated in the drawings contains four pairs of punching-arms arranged to punch four holes in a boot-quarter 75 at equal distances from each other and from the curved edge of the boot-quarter, and the gages r², r⁴, t², and t⁴ may be independently adjusted to properly locate the boot-quarter between the punching-tools. I do not wish, 80 however, to be limited to the precise number of punching-tools or operating-bars herein described, and shown in the drawings, as it is obvious that the number of pairs of arms I and J may be increased to adapt the machine to punch a greater number of holes 85 without departing from the principles of my invention.

What I claim as new, and desire to secure by Letters Patent of the United States, is— 90

1. In a gang-punch the combination of a plurality of pairs of tool-carrying arms, each pair pivoted together at their rear ends, and independently pivoted to and adjustable endwise upon a common support; and means for 95 adjusting the tool-carrying ends of said arms to a greater or less distance apart at one operation.

2. The combination in a gang-punch of a plurality of pairs of tool-carrying arms, each 100 pair pivoted together at their rear ends, and independently pivoted to, and adjustable endwise upon, a common support; a suitable punch carried by the front end of one arm of each pair; a suitable anvil or block carried 105 by the other arm of each pair in position to coöperate with said punch; and means for vibrating one arm of each pair at one operation.

3. The combination in a gang-punch of a 110 plurality of pairs of tool-carrying arms, each pair pivoted together by independent pivots at their rear ends; serrated seats for supporting the rear ends of said arms, and provided with a series of slots extending in the 115 direction of the lengths of said arms; an independent plate having a serrated under surface, pivoted to the rear end of the lower arm of each pair by a pivot extending through 120 one of said slots; and a clamping-nut for securing said arms in the desired adjusted position.

4. The combination in a gang-punch of the serrated support a provided with a plurality 125 of slots b; a plurality of plates c having their under surfaces serrated; a plurality of pairs of arms I and J pivoted together and to the plates c at their rear ends; the punches e set in the front ends of the arms I; the anvils or cutting-blocks f set in the forward ends of 130 the arms J; the table B provided with slot B'; the plate L provided with a plurality of diverging slots h, h, engaging said punches; means for adjusting said plate L; a clamp-

ing bolt and nut for securing said plate in its adjusted position; and means for vibrating all of the arms J in unison.

5. In a gang-punch the combination of a plurality of pairs of tool-carrying arms, each pair being pivoted together at their rear ends, one of which is vertically movable about said pivot, and is provided with a longitudinal slot between its two ends; means for adjusting each pair of arms endwise, independently of the other pairs; a rotary shaft; two eccentrics fixed on said shaft; a pair of eccentric rods operated by said eccentrics; a rod connecting the ends of said eccentric-rods and passing through the slots in said vertically movable arms; and means for intermittently rotating said eccentric-shaft.

6. In a gang-punch the combination of a plurality of pairs of tool-carrying arms, each 20 pair being pivoted together, and to a common support by independent pivots, one arm of

each pair being movable vertically about its pivot to its mate and each pair of said arms being movable laterally about its pivot to said common support; means for simultaneously adjusting the movable ends of all of said pairs of arms to a greater or less distance from each other; the gages r^2 and r^4 carried by one of said adjustable arms; the gages t^2 and t^4 carried by another of said adjustable arms; and mechanism for imparting to one arm of each pair a vibratory motion in a vertical plane.

In testimony whereof I have signed my name to this specification, in the presence of 25 two subscribing witnesses, on this 12th day of February, A. D. 1898.
